Primary Examiner — Clare E Heflin(74) *Attorney, Agent, or Firm* — Notaro, Michalos & Zaccaria P.C.(57) **CLAIM**

The ornamental design for a landscape light, as shown and described.

DESCRIPTION

FIG. 1 is a front, left, top perspective view of a landscape light showing my design therefor;

FIG. 2 is a top plan view thereof;

FIG. 3 is a bottom plan view thereof;

FIG. 4 is a right side view thereof;

FIG. 5 is a left side view thereof;

FIG. 6 is a rear elevational view thereof; and,

FIG. 7 is a front elevational view thereof.

The broken lines shown on the drawings depict portions of the landscape light that form no part of the claimed design.
